BRACKET OR HOLDER FOR SHELVES

Erling Severin Jacobsen, Haugesund, Norway,
assignor to Norsk Speilfabrikk & Glassliperi
A/S, Bergen, Norway

Original application September 9, 1948, Serial No.
48,499. Divided and this application March
21, 1951, Serial No. 217,362.

6 Claims. (Cl. 248—249)

1

The present invention relates to an improved bracket for a shelf or the like particularly adaptable for use in bathrooms or the like.

This application is a division of my application, Serial No. 48,499, filed September 9, 1948, now abandoned.

It is important in a bracket of this type that it be attractive and sturdy as well as easily installed in position as, in many cases, the brackets are installed by unskilled labor as accessories after a building has been completed. The bracket is generally used to support a shelf made of glass or porcelain.

Heretofore, in many instances, such brackets have been cast of solid metal; stamped out of sheet metal; or bent to a finished form from sheet metal strips. In the latter case the various strips often are soldered together to form a supporting bracket for the shelf. Accordingly, such brackets often have been difficult to fabricate.

An object of the present invention is to provide a bracket for supporting a glass shelf or the like which may be rigidly made of a wire structure formed from a single length of metal wire or light-weight bar.

Another object of the present invention is to provide an improved bracket for a shelf in which the bracket is also adaptable to support a mirror.

Still another object of the invention is to provide an improved bracket which is simple and economical in manufacture, easy to install and durable in use.

In accordance with the invention, the foregoing objects are accomplished by providing a bracket for supporting a shelf in which a single length of comparatively stiff wire is bent to form two substantially parallel loops, each having at least two legs, one leg of each loop being bent outwardly to form a supporting arm for the shelf; the tips of the supporting arms being bent upwardly to form shelf retaining ends. Fastening means are provided for attaching the bracket to a supporting surface.

In accordance with a preferred embodiment of the invention the wire structure is adapted to be formed so as to provide a railing along the outer edges of a glass shelf so as to prevent articles from slipping off from the edge of the shelf.

Another feature of the invention is the provision of means for adding to the rigidity of the structure in which the reinforcing member may be finished with a mirror surface.

Other objects and advantages of the invention will be apparent from the following description and from the accompanying drawings which

2

show, by way of example, embodiments of the invention.

In the drawings,

Figure 1 is a perspective view of a bracket constructed in accordance with the invention in which the wire structure provides a railing for the shelf and in which the supporting loops are upwardly turned so as to provide a support for a mirror.

Figure 2 is a side view of the bracket shown in Figure 1.

Figure 3 is a detailed perspective view showing the mirror holder which acts with the mirror to reinforce the wire structure.

Figure 4 is a fragmentary view corresponding to a portion of Fig. 1, showing a modification.

In Figure 5 there is shown a metal wire or bar 201 having an intermediate portion 202 forming a front railing for the shelf and having ends 203 and 204 turned rearwardly to provide railings for the ends of the shelf. In this embodiment of the invention loops 205 and 206 are turned upwardly and supporting arms 207 and 208 are formed by turning the free ends of the loops outwardly. The supporting arms are provided with upwardly turned tips to form shelf retaining means 209 and 210. The bracket may be secured against a supporting surface by a pair of sleeve members 218 and 219 having their lower ends apertured to receive fastening screws 220 and 221. The upper ends of the sleeve members are formed with a channel cross-sectional shape and are positioned so that the open sides of the channels face inwardly thus forming a pair of longitudinally extending slots adapted to receive reinforcing means 222 which may be provided with a mirror surface.

If desired, the sleeve members 218 and 219 may be made of sheet metal, the lower portions of each having an extension 223 which may be formed to close the open side of the bottom end of the sleeve. When the bracket is installed in position against a supporting surface and the sleeve members 218 and 219 are held in spaced relationship by the reinforcing means 222 the rigidity of the structure is increased as the tops of the loops are restrained from an inward movement under the stress of the shelf load on the supporting arms 207 and 208.

In the event a mirrored surface is used on the reinforcement means for holding the upper ends of the sleeve members in spaced relationship, the mirror may be easily removed for cleaning by sliding it upwardly and removing it from the slots in the sleeve members.

In Fig. 4 there is shown a modification in which the portion of the metal wire or bar 201 that forms the railing 203 at the end of the shelf is bent to provide one or more loops 225 for receiving tooth brushes or other articles.

While the invention has been described and illustrated with reference to specific embodiments thereof it will be understood that still other embodiments may be resorted to without departing from the invention.

Furthermore, while the various embodiments of the invention have been described and illustrated as being applicable to be installed on flat supporting surfaces, it is obvious that slight modifications of the constructions might be made to adapt their use on curved surfaces, such as pillars or the like. Therefore, the form of the invention set out above should be considered as illustrative and not as limiting the scope of the following claims.

I claim:

1. A bracket for use in supporting a shelf comprising a structure formed from a length of wire having intermediate and end portions, the intermediate portion adapted to provide a front railing for the shelf, the end portions turned rearwardly from the intermediate portion to form end railings for the shelf, each of the end portions turned upwardly and thence downwardly to form a pair of upwardly extending loops, the free end of one leg of each of the loops being turned at a substantially right angle with respect to said leg so as to extend forwardly at a level below that of said railings to form supporting arms for the shelf, and the outer end of at least one of the supporting arms being turned upwardly to form retaining means for the shelf.

2. A bracket for use in supporting a shelf comprising a structure formed from a length of wire having intermediate and end portions, the intermediate portion adapted to provide a front railing for the shelf, the end portions turned rearwardly from the intermediate portion to form end railings for the shelf, each of the end portions turned upwardly and thence downwardly to form a pair of upwardly extending loops, the free ends of the loops being bent at approximately right angles so as to extend forwardly and inwardly toward one another at a level below that of the railings to form supporting arms for the shelf, the outer end of at least one of the supporting arms being turned upwardly to form retaining means for the shelf, and at least one of the end railings being formed with an approximately horizontal outwardly projecting loop adapted to support an article beside the shelf.

3. A bracket for use in supporting a shelf comprising a structure formed from a length of wire having intermediate and end portions, the intermediate portion adapted to provide a front railing for the shelf, the end portions turned rearwardly from the intermediate portion to form end railings for the shelf, each of the end portions turned upwardly and thence downwardly to form a pair of upwardly extending loops, the free ends of the loops being bent at approximately right angles so as to extend forwardly and inwardly toward one another at a level below that of the railings to form supporting arms for the shelf, the outer end of at least one of the supporting arms being turned upwardly to form retaining means for the shelf, and at least one of the end railings being formed with an approximately horizontal outwardly projecting loop adapted to support an article beside the shelf.

4. A bracket for use in supporting a shelf comprising a structure formed from a length of wire having intermediate and end portions, the intermediate portion adapted to provide a front railing for the shelf, the end portions turned rearwardly from the intermediate portion to form end railings for the shelf, each of the end portions turned upwardly and thence downwardly to form a pair of upwardly extending loops, the free ends of the loops being bent at approximately right angles so as to extend forwardly and inwardly toward one another at a level below that of the railings to form supporting arms for the shelf, the outer end of at least one of the supporting arms being turned upwardly to form retaining means for the shelf, a pair of vertical sleeve members each adapted to receive one of the loops, and a reinforcing member interposed between the sleeve members to prevent the legs of the loops from spreading.

5. A bracket for use in supporting a shelf comprising a structure formed from a length of wire having intermediate and end portions, the intermediate portion adapted to provide a front railing for the shelf, the end portions turned rearwardly from the intermediate portion to form end railings for the shelf, each of the end portions turned upwardly and thence downwardly to form a pair of upwardly extending loops, the free ends of the loops being bent at approximately right angles so as to extend forwardly underneath the shelf to form supporting arms for the shelf, the outer end of at least one of the supporting arms being turned upwardly to form retaining means for the shelf, a pair of vertical sleeve members adapted to receive said loops the upper portions of the sleeve members being formed of channel cross-section providing longitudinally extending slots, and a reinforcing member positioned in the slots so that the loops are restrained against an inward twisting motion resulting from a load on the shelf.

6. A bracket for supporting a shelf on a vertical surface, said bracket being formed of a single length of wire bent to provide the following portions, starting from the middle of said length of wire and proceeding toward both ends, a central horizontal portion providing a front railing for the shelf, rearwardly extending horizontal portions providing end railings for the shelf, portions extending approximately vertically and then doubled back on themselves to form hairpin loops disposed in a vertical plane parallel to said vertical surface, and end portions extending forwardly from said vertical plane and lying in a horizontal plane below said railing portions, said end portions forming supporting arms for the shelf, the outer end of at least one of said supporting arms being turned upwardly to form retaining means for said shelf.
